UNITED STATES PATENT OFFICE.

HENRY L. FEDDERSEN, OF SAN FRANCISCO, CALIFORNIA.

DRAWCUT SCISSORS.

Application filed September 30, 1924. Serial No. 740,853.

To all whom it may concern:

Be it known that I, HENRY L. FEDDERSEN, a citizen of the United States, and a resident of San Francisco, county of San Francisco, State of California, have invented a new and useful Drawcut Scissors, of which the following is a specification.

This invention relates to scissors and hand shears generally and has for its object a special joint construction which will impart a relative longitudinal motion to the blades during the cutting action whereby a "draw cut" is effected with a resulting increased efficiency in such devices.

15 In the drawings hereto Figure 1 shows a pair of scissors with blades half opened and with the pivot nut and washer removed to reveal the peculiar construction of the pivot which produces the draw cut action.

Figure 2 is a section of the joint taken along the line 2—2 of Figure 1.

Figure 3 is the joint as shown in Figure 1, but with the blades closed and with the 25 near blade drawn to the end of its slot which permits of the draw cut action.

Figure 4 shows a modified joint providing for a greater sliding or draw cut action than the construction shown in Figure 1.

Figures 5 and 6 show the same joint as do the other figures but with a sliding block over the pin to prevent wear.

In the figures 1 is the upper blade, 2 35 the lower blade, and 3 and 4 are the respective handles of the blades.

At 5 is a pivot pin for holding the blades together and permitting their pivotal action.

40 This pin has an enlarged portion 6 and two reduced ends, the outer one being threaded as shown in Figure 2 and the other one being passed through blade 2 and firmly riveted thereto by heading over as shown 45 at 7.

At 8 is a notch formed in the edge of the rivet hole so that the spreading of the rivet will lock therin as indicated so that the 50 riveted pin will be securely locked against turning.

Blade 1 fits against blade 2 over this pin, but instead of having a plain round pivot hole is slotted as shown at 9 and the slot 55 is formed with a gear tooth notch 10 on one side receiving freely a single gear tooth

11 which projects from the enlarged portion 6 of the pin.

The position of this gear tooth in relation to the blade to which the pin is riveted is predetermined and is such that when the 60 scissors blades are about half open, as shown in Figure 1, the tooth will project at right angles to the run of the slot in blade 1, and when the blades are closed will be in the position shown in Figure 3 drawing the 65 blade to the end of the slot.

By this arrangement it is manifest that upon opening and closing of the scissors, blade 1 will be moved longitudinally back and forth relative to blade 2, thus effecting 70 a draw cut action.

The amount of the draw cut motion is governed by the distance of the tooth 11 outwardly from the center of the pin, and if this is made relatively great several small 75 teeth may be used in place of the single tooth as indicated in Figure 4 of the drawings, where the tooth 11 of Figure 1 is replaced by a small gear segment having several small teeth 11' thereon and meshing with 80 similar teeth 10' formed on the side of the slot.

In contemplating the pivotal joint as described it will be seen that the pin 5 is liable to wear on account of its rubbing along the 85 edge of the slot in blade 1 and to overcome this I optionally reduce the height of the shoulder portion 6 of the pin and drop over the pin a plate 14 free to revolve on the pin and free to slide in the slot so that a 90 long surface is presented to both edges of the slot, wear is thus prevented and no backlash is developed through long use.

It is evident without illustration that a roller may be used in place of the sliding plate but the plate is simple and has longer life.

Having thus described my invention, it will be seen to effect the desired objective in a very simple manner having the outward 100 appearance of an ordinary scissors, for when in use a washer 12 covers the slot and a nut 13 provides for adjustment of the blades to a proper working friction.

I claim:

1. A pair of scissors or shears comprising two blades pivotally and slidably secured together, the pivotal connection comprising a shouldered pin secured fixedly to one of the blades with the shoulder projecting into 110

105

110

- a slot in the other blade, a projection from the shouldered portion of the pin engaging a notch in the edge of the slot, a threaded reduced portion of the pin extending through the slotted blade and having a nut thereon for securing the joint, and a plate through which said pin passes, said plate being free to rotate on the pin and to slide in the slot.
- 10 2. A pair of scissors or shears comprising two blades pivotally and slidably secured together, the pivotal connection comprising a shouldered pin secured fixedly to one of

the blades with the shoulder projecting into a slot in the other blade, a projection from the shouldered portion of the pin engaging a notch in the edge of the slot, a threaded reduced portion of the pin extending through the slotted blade and having a nut thereon for securing the joint, and a plate through which said pin passes, said plate being free to rotate on the pin and to slide in the slot, the head end of said pin being riveted and extended into a notch in one of the blades to prevent it from rotating.

HENRY L. FEDDERSEN.
